United States Patent

Des. 237,666
Patented Nov. 18, 1975

237,666

RAZOR HOLDER

Clemens A. Iten, Staunton, Va., assignor to Philip Morris Incorporated, New York, N.Y.

Filed Mar. 11, 1974, Ser. No. 449,612

Term of patent 14 years

Int. Cl. D6—06

U.S. Cl. D6—88

FIG. 1

FIG. 2

FIG. 3

FIG. 1 is a front elevational view of a razor holder showing my new design, with the razor shown in broken lines for illustrative purposes only;

FIG. 2 is a side elevational view thereof; and

FIG. 3 is a perspective view thereof.

I claim:

The ornamental design for a razor holder, as shown.
